Primary Examiner — Michael C Stout*Assistant Examiner* — Melvin L Davis(74) *Attorney, Agent, or Firm* — Boyle Fredrickson, S.C.(57) **CLAIM**

The ornamental design for a trampoline frame as shown and described.

DESCRIPTION

FIG. 1 is a front perspective view of a trampoline frame having legs and showing the new design;

FIG. 2 is a top plan view thereof;

FIG. 3 is a front elevation view thereof; and,

FIG. 4 is an enlarged broken away perspective view of a front leg of FIG. 1.

The dot-dash boundary lines shown in FIGS. 1 and 4 demarcate claimed areas that have been enlarged for clarity while the lines themselves do not form part of the claimed design.

The broken line showing of the trampoline frame is for the purpose of illustration portions of the article and forms no part of the claimed design.
